UNITED STATES PATENT OFFICE

ROY C. BAKER, OF WOLLASTON, MASSACHUSETTS, ASSIGNOR OF ONE-FIFTH TO LOUIS A. JONES, OF BELMONT, MASSACHUSETTS

BOOKBINDING

Application filed December 31, 1928. Serial No. 329,504.

This invention relates to book bindings, and will be best understood by reference to the following description, when taken in connection with the accompanying drawings illustrating a completely bound book and component parts thereof embodying the invention, while its scope will be more particularly pointed out in the appended claims.

In the drawings:

19 Fig. 1 is a perspective view of a book having a binding embodying my invention;

Fig. 2 is a perspective view of a super embodying one feature of the invention, together with a back lining attached thereto;

15 Fig. 3 is a perspective view of a group of signatures prepared for binding;

Fig. 4 is an elevation of a portion of the super on an enlarged scale as compared with Fig. 2;

20 Fig. 5 is a perspective view of the signatures with the super and back-lining;

Fig. 6 is an elevation of a casing embodying another feature of the invention, comprising a pair of cover boards with reinforcing strips applied to their adjacent or hinge edges, and covered with material which connects the boards; and

Fig. 7 is a sectional view on an enlarged scale on line 7—7 of Fig. 6.

30 Referring to the drawings, and to the embodiment of the invention which is illustrated therein, there is shown in Fig. 3 a group of signatures 10 prepared in the usual manner, and in readiness to be case bound. In Fig. 6, there is shown a case comprising cover boards 11 covered in the customary way with sheet material 12 such as cloth or leather, which connects the cover boards to each other and is folded about the edges and onto the inner faces of the cover boards in the usual manner.

One weakness of bindings, as heretofore made, is that the super which forms the cover hinges is secured by an adhesive directly to the cover boards which are usually made of relatively soft, laminated stock. Very often, the super tears away from the cover boards, taking with it a layer of the cover board. One feature of my invention is the provision of strips 13 of kraft paper or cloth, folded to

embrace the hinge edge of each cover board (see Fig. 7), and fastened to both faces and to the edge of the cover board by a suitable adhesive. When, therefore, the super is fastened to these strips, the strain is transmitted to the entire cover board, and the durability of the binding is greatly increased, because there is little or no tendency for the super to tear away from the cover board.

In Fig. 6, there is shown a complete casing having a usual cover back-lining 14, secured by an adhesive to the covering 12, and having its ends overlapped by the turned over margins of the covering. This casing, as shown, is of usual construction, except that the cover boards 11 are provided with the described strips 13.

The usual method of binding is to secure the head bands to the signatures, then to secure the super to the signatures between the head-bands, and finally to secure the back-lining to the super. In the method disclosed in Letters Patent No. 1,665,049, issued to me April 3, 1928, the back-lining has the head-bands secured to it first, and the back-lining is secured to the super before the latter is secured to the backs of the signatures. Either of these methods may be employed in connection with my present invention. In Fig. 2, the method disclosed in my aforesaid patent is employed, and there is shown a back-lining 15 to which head-bands 16 have been attached prior to the attachment of the back-lining to the novel super now to be described.

Of course, the strongest bindings heretofore employed have been sewed or laced; but such bindings are relatively expensive, and the cost is prohibitive for books of some classes. In accordance with my present invention, I employ a super which produces an exceptionally strong binding, far superior to the binding employing the super heretofore employed, and approaching, if not equalling, in strength sewed or laced bindings. To this end, I provide a super 17, which may be muslin or crash starched after weaving to give it stiffness and strength, but while supers, as heretofore made, have been made of plain cloth without reinforcement, I have provided the super with rein-

forcing members 18, whose durability, tensile strength and resistance to the wear of bending are greater than that of the remainder of the super.

5 These reinforcing members may be applied to or incorporated in the super in any appropriate manner, as by incorporating them in the fabric while it is being woven. One convenient method is to provide the 10 warp with reinforcing members, such as strings or cords relatively larger and heavier than the remaining strands of the warp. In Fig. 4, the super is shown as a sheet of muslin having between the reinforcing warp 15 members 18 other warp members, such as threads 19, and there are similar weft threads 20 interwoven with the warp threads and with the heavy reinforcing members 18.

When the super is applied, these reinforcing members extend transversely of the signatures and of the hinge edges of the cover boards (see Figs. 1 and 5). These reinforcing members strengthen the hinges enormously, and impart to them a durability comparable with those of a sewed or laced binding. The cost of this novel super, moreover, compares very favorably with the cost of an ordinary super, and adds no labor cost to the binding operations. When this novel 25 super is secured by a suitable adhesive to the strip 13, and to the backs of the signatures, there is produced a binding which possesses a degree of resistance to wear and rough handling, which is quite remarkable, and yet, owing to its slight expense, may be employed 30 in the binding of books which are sold on a highly competitive basis. School books, which fall in this class, but which are subjected to rough handling and much abuse, are given tremendous increase of resistance 35 to wear and shock.

The end lining papers 21 are secured by a suitable adhesive to the cover boards 11, to the margins of the super 20, and to the folded over edges of the covering 12. The bulk of the reinforcing strands 18 is not great enough to produce objectionable irregularity of the surfaces of the lining papers.

Having thus described one embodiment 50 of the invention, but without limiting myself thereto, what I claim and desire by Letters Patent to secure is:—

1. A book wherein there is a group of signatures, a pair of cover boards, and hinges 55 connecting said cover boards to said signatures, characterized by the fact that each hinge comprises a sheet of material having a series of reinforcements extending across the space between said signatures and the adjacent cover, said reinforcements having a substantially greater durability than that of the remainder of said sheet.

2. A book wherein there is a set of signatures and a super attached thereto, characterized by the fact that said super comprises 60

a sheet of material having a series of reinforcements extending transversely of the backs of said signatures, said reinforcements having a durability substantially greater than that of the remainder of the super.

3. A book wherein there is a set of signatures and a super attached thereto, characterized by the fact that said super comprises a sheet of material having a series of members extending transversely of the backs of said signatures, said members having a substantially greater degree of resistance to the wear caused by bending than is possessed by the remainder of said super.

4. A book wherein there is a set of signatures and a super attached thereto, characterized by the fact that said super comprises a sheet of material having a series of members extending transversely of the backs of said signatures, said members having a tensile strength substantially greater than that of the remainder of the super.

5. A book wherein there is a set of signatures and a super attached thereto, characterized by the fact that said super comprises a sheet of woven material having its warp disposed transversely of the backs of said signatures and comprising a series of warp members whose durability is substantially greater than that of the remaining warp members.

6. A book wherein there is a set of signatures and a super attached thereto, characterized by the fact that said super comprises a sheet of woven material having its warp disposed transversely of the backs of said signatures and comprising a series of spaced cords, and threads of smaller cross section than said cords in the spaces between said cords.

In testimony whereof, I have signed my name to this specification.

ROY C. BAKER.
